UNITED STATES PATENT OFFICE.

ROBERT M. DIXON, OF EAST ORANGE, NEW JERSEY, ASSIGNOR TO THE SAFETY CAR HEATING AND LIGHTING COMPANY, OF NEW YORK, N. Y.

DESIGN FOR A CASING FOR HEATING APPARATUS.

SPECIFICATION forming part of Design No. 26,181, dated October 12, 1896.

Application filed March 22, 1894. Serial No. 504,726. Term of patent 14 years.

To all whom it may concern:

Be it known that I, ROBERT M. DIXON, a citizen of the United States, residing at East Orange, Essex county, in the State of New Jersey, have invented and produced a new and original Design for a Casing for Heating Apparatus, of which the following is a description.

The leading feature of my design is a casing for heating apparatus of essentially the exterior configuration and representation shown in the accompanying drawing.

In the drawing which, as aforesaid, represents my design, A A are sections of cylindrical shape terminating at each end in the members B and C, of the external form of

ovaloid prisms, from which project short cylinder-shaped sections a a a a at right angles to the cylindrical sections A A. Short sections D of cylindrical form project from the ovaloid prismatic member B on the side thereof opposite to the sections A A and in the same linear direction.

What I claim is—

A casing for heating apparatus consisting of the peculiar exterior configuration herein shown and described.

ROBERT M. DIXON.
